UNITED STATES PATENT OFFICE

HAMILTON P. RICHARDSON, OF CHICAGO, ILLINOIS.

SLEEPING-CAR HAVING UPPER AND LOWER BERTHS.

1,098,332.

Specification of Letters Patent.

Patented May 26, 1914.

Application filed November 9, 1912. Serial No. 730,394.

To all whom it may concern:

Be it known that I, HAMILTON P. RICHARDSON, citizen of the United States, residing at Chicago, county of Cook, State of Illinois, have invented a new and useful Improvement in Sleeping-Cars Having Upper and Lower Berths, of which the following is the specification.

The object and nature of the invention are to convert a section of sleeping car having upper and lower berths into two dressing rooms, by turning the berths on end on the floor as and for partitions, and to reconvert the same.

Figure I of the drawing shows a view in elevation of a section of the car with the means referred to. Fig. II shows an end view of said section.

Figure 3 indicates the car side, 4 the panel, 5 the window, 6 the lower berth made up as a berth, 7 the partition from the lower berth, 8 the upper berth made up, 9 the partition from the upper berth, 10 the berth supporting pins, 11 the rollers, 12 the bearing springs, 13 the slots, 14 the rails, 15 the pin bearings, 16 the roller spindles, 17 the pulley block, 18 its spring, 19 the foot boards, 20 the chains, 21 the shoulders, 22 the upper berth division, 23 the hinge, 24 the lower berth aisle leg, 25 the dovetail slides, 26 the angle bar, 27 the horizontal bed springs, 28 the lower berth arm.

Back of each berth (6 and 8), in horizontal position a slot extends in the car side 35 (13). Back of each berth in vertical position, when used for a partition, a slot extends in the car side (13). The lower berth partition is located at the right end of the section (7), and the upper berth partition 40 is located near the middle of the section (9). The partitions extend from the floor to the ceiling. It is apparent that these positions might be reversed and the lower berth be located at the left end or the middle and the 45 upper berth at either end.

Each berth is loosely mounted on two pins (10), each pin passing through one slot and rigidly mounted in connection with three rollers (11) on rails (14) parallel with the 50 slots in the car side, two rollers on one rail on one side of each slot and one roller on a rail on the opposite side of the slot.

The lower berth vertical slot begins at the height of the berth from the floor and extends to the top of the partition or the ceiling, and the lower berth horizontal slot be-

gins at a point distant from the left end of the section equal to the height of the lower berth from the floor and extends to the said vertical slot. The upper berth vertical slot 60 begins at the height of the upper berth from the floor and extends to a distance from the floor equal to the distance of this slot from the left end of the section, and the upper berth horizontal slot begins at a distance 65 from the right end of the section equal to the drop of this berth from the ceiling, or the top of the partition, and extends to the said vertical slot. The rails extend beyond the slots at both ends thereof only far enough 70 to carry the rollers respectively.

The pins (10) are mounted in the berths at the points of beginning of the slots with the berths in the horizontal positions.

The action is that the berths turn on the 75 pins and move in the slots and on the rails together. The left end of the upper berth is lowered thirty degrees, the right end of the lower berth is raised and the lower berth is brought to the vertical position as a partition, after which the upper berth is lowered to the vertical position as a partition. It is apparent that the order of action might be reversed and the lower berth raised thirty 80 degrees and the upper berth lowered to 85 the vertical position, and then the lower berth raised to the vertical position.

The berths are reconverted by reverse steps. The upper berth is raised sixty degrees, the lower berth is lowered to the horizontal 90 position, then the upper berth is raised to the horizontal position.

For the firm mounting of the berths the pins and their bearings (15) in the berth frames are long. The roller spindles for 95 each pin (16) are rigidly connected to a half elliptic spring (12), one spindle at each end and the middle of each such spring, the ends of the spindles projecting from one and the same side of the spring, and 100 the berth pin is an extension of the middle spindle. The rollers for each pin and their rail webs lie in one plane parallel with the car side, with the tread of the rails facing each other and the rollers between the rails. 105 It is apparent that the rails might be laid with the bases contiguous between the rollers, or that one rail might be laid between its rollers and the panel, and the two rails and the rollers bearing on them be in two 110 planes at right angles. The springs are compressed in position. The two end roll-

ers for each pin bear on one rail and the middle roller is guided and gripped by the other rail and moves in the opposite direction to the two rollers.

5 The upper berth is counterbalanced by a wire pulley block in the car side (17), hauling on a spring (18), with a number of pulleys to limit the tension on the spring, and to balance the upper berth in all positions 10 with occupant. The berths have foot-boards (19), contributing to the support of the occupants. The berths are converted by the porter and the movement is graduated to degrees and will be found as safe and easy 15 as the movement of reclining chairs in other cars. The covers can be held by straps.

The upper berth chains (20) may be removed or the chains may be detached and reattached. The upper berth frame will be 20 in two hinged pieces, divided lengthwise, on the line of short bend of the panel (22), near the car side, and the pins through frame and slots will not be strained in converting. The lower berth parts will be rigidly connected, the back and seat pieces joined with 25 horizontal, dovetailed slides (25), and an

angle bar bearing made next car side (26). The berth springs will be horizontal, coil springs (27), instead of box springs, and clear floor space of thirty inches by thirty- 30 six inches will be provided for each room. Wash basin lockers can be put in beneath windows.

I claim:

In a sleeping car having upper and lower 35 berths, each berth loosely mounted on two pins, each pin rigidly mounted on two roller spindles, each roller bearing on a rail in the car side, the rails extending upwardly for one pin rollers for the lower berth and 40 downwardly for one pin rollers for the upper berth, and laterally thereto respectively for the other pin rollers, said berth pins, rollers and rails being adapted to permit the conversion of the berths into room 45 partitions at the middle and the end of the sections.

HAMILTON P. RICHARDSON.
